UNITED STATES PATENT OFFICE.

WILLIAM W. MACFARLANE, OF PHILADELPHIA, PENNSYLVANIA, ASSIGNOR TO MACFARLANE COMMUNICATIONS CORPORATION, OF NEW YORK, N. Y., A CORPORATION OF DELAWARE.

ELECTRORESPONSIVE DEVICE.

1,402,305.

Specification of Letters Patent.

Patented Jan. 3, 1922.

Application filed September 20, 1917. Serial No. 192,298.

To all whom it may concern:

Be it known that I, WILLIAM W. MACFARLANE, a citizen of the United States, and a resident of Philadelphia, county of Philadelphia, and State of Pennsylvania, have invented certain new and useful Improvements in Electroresponsive Devices, of which the following is a specification.

The present invention relates to current 10 conducting members especially of the type known as electroresponsive devices.

This application is a continuation in part 15 of my application Ser. No. 867,316, filed October 19, 1914, and Ser. No. 82,861 filed March 8, 1916.

The main object of this invention is to provide a current carrying member that will afford a low resistance path of current of relatively large volume in such manner 20 that a relatively powerful effect, such as a magnetic field, may be created by means of current of low voltage.

One feature of the invention consists in a current conducting member having the formation of a hollow helix adjacent convolutions of which are separated from each other by an air gap. In the particular form in which the invention is herein clothed, it consists of a translating device 30 having a core around which extend, in helical formation, a conductor having convolutions of a ribbon or strip-like character and of relatively large cross sectional area to afford a low resistance path for an electric 35 current.

Other features of the invention will appear as the specification proceeds.

In the accompanying drawings:

Figure 1 is a side elevation of an electro- 40 magnet embodying the invention, one end of said magnet being shown in cross section.

Figure 2 is a top plan view of a modified 45 form of the invention also shown partly in section.

Figure 3 is a transverse sectional view on the line 3—3 of Figure 2.

In Figure 1, 1 represents a current conducting member extending in helical form- 50 ation around a core 2 and constituting an electromagnet. The convolutions of helix 1 are preferably formed by cutting a deep helical groove 3 in a bar of copper or other conducting material, the removal of the

metal from the groove leaving the convolu- 55 tions 4 forming a coil. To separate the convolutions individually from each other and to produce a hollow helix the central portion of the bar is bored out either before or after the helical groove is cut. In effect, 60 therefore, the coil consists of a ribbon or strip-shaped band of metal of relatively rigid material extending in helical forma- 65 tion around a central axis. The air gap 3 between adjacent convolutions of the coil 65 may be of sufficient amplitude to insulate them from each other; but, in order to prop- erly insulate core 2 from the coil, a suitable insulating sleeve 5 is employed.

Any suitable means may be utilized for 70 conducting current to and from the coil. In Figure 1 these elements take the following form: standards 6 are provided with open- 75 ings for the reception and support of the coil and these standards may in themselves constitute current conducting members to and from which current may be transmitted by means of cables 7. Under the control of core 2 and at each end thereof, there is a polarized armature 8 pivotally supported 80 at 9, each of said armatures being adapted to engage contact 10 to complete a circuit represented by conductors 11 and 12. In the form here disclosed, current flowing in one direction through the device will cause core 85 2 to attract one of the armatures 8 and to repel the other one. When the current is re- 90 versed, the opposite effect will be produced, as will be understood. It will also be understood that contacts 10 and armatures 8 90 are properly insulated from standards 6.

In the form of the invention shown in Figure 2, the construction of the coil or helix is substantially the same except that the standards are omitted, a portion of the 95 bar 25 from which the helix is produced being left at each end of the device and the coil being integrally formed with said end pieces. The current conducting member here is properly insulated from the general 100 supporting member 26 and has current transmitted to it by means of conductors 7, as before. The core 2, in this case, is pro- 105 vided with forwardly extending pole mem- bers 13, one of which passes through the supporting member 25 and is properly insulated therefrom at 27 so that extensions 13 may, in addition to constituting a magnetic

core, form a current conducting member. It will be understood that by passing current through the device in a given direction, one of the pole extensions 13 will attract armature 14 which is a permanent magnet and close a circuit represented by conductor 18, pole piece extension 13, contact member 16 and conductor 20. If current is passed through the device in the opposite direction, the armature will bring the contact member 15 against the other pole extension 13 and will thus close a circuit leading to conductor 19. To maintain armature 14 in mid-position, springs 21 may bear against 10 the rear extension 17 thereof. 15

I claim:

An electro-magnetic translating device including: a current carrying member consisting of a single layer of convolutions of relatively rigid material, hollow housings of 20 current conducting material in which the ends of the carrying member are anchored, a core extending through the current carrying member and housings, binding posts on the housings, and an armature under the influence of the core. 25

Signed at New York, in the county of New York and State of New York, this 18 day of September, 1917.

WILLIAM W. MACFARLANE.
